UNITED STATES PATENT OFFICE

JOHN WEBER, OF TOLEDO, OHIO, ASSIGNOR, BY MESNE ASSIGNMENTS, TO THE AMERICAN-NATIONAL COMPANY, OF TOLEDO, OHIO, A CORPORATION OF OHIO

DESIGN FOR A WHEEL FOR JUVENILE VEHICLES

Application filed January 20, 1930. Serial No. 34,187. Term of patent 14 years.

To all whom it may concern:

Be it known that I, JOHN WEBER, a citizen of the United States of America, residing at Toledo, in the county of Lucas and State of Ohio, have invented a new, original, and ornamental Design for Wheel for Juvenile Vehicles, of which the following is a specification, reference being had therein to the accompanying drawings, forming a part thereof, in which—

Figure 1 is a plan view of the wheel; and Figure 2 is a perspective view thereof.

The dominant feature of the design is the provision of a hub of massive appearance having a diameter substantially greater than the distance between the circumference of the hub and the circumference of the rim of the wheel.

I claim:

The ornamental design for a wheel for juvenile vehicles, substantially as shown and described.

JOHN WEBER.
